UNITED STATES PATENT OFFICE.

LYMAN KENT DAVIS, OF SPRINGFIELD, ILLINOIS.

DESIGN FOR A FOB OR SIMILAR ARTICLE.

Application filed May 4, 1925. Serial No. 13,310. Term of patent 14 years.

To all whom it may concern:

Be it known that I, LYMAN KENT DAVIS, a citizen of the United States, residing at Springfield, in the county of Sangamon and State of Illinois, have invented a new, original, and ornamental Design for a Fob or Similar Article, of which the following is a specification, reference being had to the accompanying drawing, forming a part thereof.

I claim:

The ornamental design for a fob or similar article, as shown.

LYMAN KENT DAVIS.
